Primary Examiner—Terry A Wallace*(74) Attorney, Agent, or Firm*—David Simmons(57) **CLAIM**

The ornamental design for a bottle insulator with integral bottle cap remover, as shown and described.

DESCRIPTION

FIG. 1 is a front view of an embodiment of a bottle insulator with integral bottle cap remover in accordance with the present invention;

FIG. 2 is a rear view of the bottle insulator with integral bottle cap remover shown in FIG. 1;

FIG. 3 is a left side view of the bottle insulator with integral bottle cap remover shown in FIG. 1, wherein the right side view is a mirror image of the left side view;

FIG. 4 is a top view of the bottle insulator with integral bottle cap remover shown in FIG. 1; and,

FIG. 5 is a bottom view of the bottle insulator with integral bottle cap remover shown in FIG. 1.
